UNITED STATES PATENT OFFICE.

CHARLES W. MERRILL, OF LEAD, SOUTH DAKOTA.

CONTAINER FOR PRESSURE-FILTERS.

No. 856,596.

Specification of Letters Patent.

Patented June 11, 1907.

Application filed April 14, 1906, Serial No. 311,650.

To all whom it may concern:

Be it known that I, CHARLES W. MERRILL, a citizen of the United States, and a resident of Lead, in the county of Lawrence, State of South Dakota, have invented new and useful Improvements in Containers for Pressure-Filters, of which the following is a specification.

My invention relates to an improvement in containers for use in connection with apparatus for separating unfilterable material from a mixture of filterable and unfilterable material, and particularly to improvements in pressure filters in which the separation and treatment of such material is effected, and is primarily intended to apply to that class of filter press in which cleansing, precipitating or other material is introduced through independent openings into the containers.

In two applications for Letters Patent of the United States heretofore filed by me in the United States Patent Office, one being Serial No. 252,524 and the other being Serial No. 304,722, I have described and claimed filter presses of the type of those above referred to, and the present invention relates to improvements in forms of containers for use in connection with presses of the character of those described in the said applications. In the aforesaid applications I have shown and described containers provided with one or more openings at a convenient point or points, preferably in the bottom, in, or near which a rotative pipe is placed provided with suitable nozzles or nipples through which a cleansing medium is introduced at varying angles and degrees through the openings into the contents of the container. The present invention embraces a container in which the same effect is produced by a variety of slightly different means.

The present invention consists in substituting for the rotative pipe and nozzles, passages in the container walls through which the cleansing medium may be introduced in any desired direction or directions, or in any desired quantities.

The invention will be best understood with reference to the accompanying three sheets of drawings, which show containers of the same general type as those described and claimed as a part of the aforesaid applications embracing the aforesaid invention.

In the drawings Figure 1 represents a vertical cross-section of one type of container

embodying the present invention; Fig. 2 an elevation of a container embracing it in a slightly modified form; Fig. 3 a vertical cross-section of the same construction shown in Fig. 1, but provided, however, with two outlet openings; Fig. 4 a vertical section of a different slightly modified form; Figs. 5 and 6, vertical sections of still different modifications, showing the inlet openings along the sides and on the top of the container; Figs. 7 and 8, vertical cross-sections of still further modifications, the former showing the openings extending entirely around the inner periphery of the container, and the latter showing them similarly placed only at varying angles; Fig. 9 a vertical longitudinal section of the wall of a container on the line 9 of Fig. 10 looking in the direction of the arrows, showing the row of openings *q*—*q* inclined in pairs toward each other; Fig. 10 a plan view of the openings shown in Fig. 9; Fig. 11 a plan view of a portion of the inner wall of the container showing a single row of openings *q*; Fig. 12 a similar plan view showing two rows of openings *q* in the surface, arranged so as to be staggered with respect to each other. Fig. 13, a vertical section of a container similar to that shown in Fig. 1, except that the continuous washout channel is replaced by an opening in the bottom of the container closed by a gate; Fig. 14, a vertical section of a container similar to that shown in Fig. 4, except that the continuous channel is replaced by an opening closed by a gate. Fig. 15, a vertical section of a container similar to that shown in Fig. 5, except that the continuous channel is replaced by two openings closed by gates.

Similar letters refer to similar parts throughout the several views.

In the present application the containers are shown adapted for use in what is known as the "closed delivery" type of filter press, as distinguished from the "open delivery" type, although I may use either type. As in the other applications above referred to, *x* is the frame of the container which may be square in cross-section or any other suitable shape, *o* is an opening or inlet either in a ring formed preferably in the bottom of the container, or in the bottom of the container itself through which the semi-solid or the unfilterable material hereinafter called for convenience the "unfilterable component" is removed from the containers, and which, in the former case, when a series of contain-

ers is put together in a filter press, makes a continuous passage through the press which is closed at the ends in any convenient manner and can be arranged to discharge into any suitable receptacle. *a* is a corresponding inlet for treating the unfilterable component in place with liquids, vapors or gases and which is preferably placed at either or both upper corners of the container or at all four corners as shown, and in like manner forms a continuous passage or passages when the containers are put together in the filter press.

d is an inlet in a ring 13 formed on the upper wall of the container through which the material to be filtered is introduced which inlet is of the same general character as the outlet *o* and becomes a continuous passage when the containers are put together within the filter press, and is provided with the ports 9 through which the material is introduced from the passage *d* into the chamber, the channels *o* and *d* may be consolidated and one channel used for both purposes.

The details of construction above set forth are applicable to all containers of the different types hereinafter described.

In the construction of container embodying the present invention and shown in Fig. 1, *q* represents a series of openings which are connected with passage *r* passing longitudinally along and within the bottom wall of the container and emerging from the channel *k*. In this construction the liquids, vapors or gases or other washout medium, enter through the channel *k*, pass into the channel *r*, and thence emerge vertically upward through the openings *q* into the interior of the container, and the unfilterable component of the container, is washed out through the channel *o*. In Fig. 2, the construction is the same, except that the positions of the lower openings *a a* and the channel *k* are slightly changed.

In Fig. 3, two outlets *o o* are shown, and the openings *q* are arranged on either side thereof.

In Fig. 4, two channels *k* are provided one on either side of the container, and openings *q* emerge therefrom in the manner shown in that figure.

In the construction shown in Fig. 5, two channels *k* are shown one on either side, and a channel *r* connected with each. The openings *q* emerge from the channels *r* in the side walls of the container into the container as before, and in this way the cleansing medium is introduced cross-wise through the container.

In the form of container shown in Fig. 6, two channels *k* are shown on either side, and the channels *r* are carried up to the top of the container and cleansing medium introduced through openings in the top as well as in the sides. The same is true of the construction shown in Fig. 7, with the addition

that the opening *r* extends through the bottom of the container and the openings are provided in this portion of the container in the same manner as in Fig. 1.

Fig. 8 shows a continuous opening *r* connecting with two openings channels *k* and running entirely around the interior of the container, and provided with inclined openings *q* for giving any desired angularity to the direction of the cleansing medium and in this case causing it to converge toward the center of the container.

The Figs. 9 and 10 show the openings *q* in an inclined position so as to concentrate the two streams in the same direction and Figs. 80 11 and 12 show the openings in a continuous line along the periphery of the container in the former or in two lines staggered with respect to each other in the latter.

In the construction shown as Figs. 13, 14 85 and 15, the construction of the openings through which the washing out medium enters, is the same as that shown in Figs. 1, 4 and 5, but the continuous channel *o* through which the washout is effected, is replaced by an opening *o* in the bottom of the container, which opening is closed in each case by means of the gate 12 which may be operated in any convenient manner. In the construction shown in Fig. 15, two such 95 gates are used. These openings need not of necessity be in the same place, nor need their direction be necessarily parallel; on the contrary two or more may be inclined toward or away from each other in either 100 direction and they may be in the same or in parallel or in any other plane or planes. Their disposition, direction, angularity and size, may vary from time to time as may be found most suitable. Any number may be 105 used in connection with any one container and they may be placed at the same or at a different angle and may be used singly or in pairs or in any desired numbers or locations.

When the containers are put together in 110 the press, the channel *k* forms a continuous opening longitudinally through the press, and it terminates in an appropriate opening in either of the press heads, and the cleansing medium is introduced into the channel 115 therefrom by suitable pipes or other devices. In all cases the washout medium enters through the channel *k*, passes into the channel *r* and thence emerges through the openings *q* into the interior of the container, 120 and passes out through the passage *o*. If necessary, one or more channels *k* may be employed, as well as one or more channels *r*, all arranged or disposed in any convenient manner or position. Any number of openings *q* may be employed, as well as any number of openings *o* and all or any portion of the interior perimeter of the container can be provided with these openings. In practice it is found preferable to have the bottom slope 130

toward the outlet or outlets, and to make the openings *q* parallel and to extend them upward from the bottom.

The method of putting the containers together and using them in a press is particularly described in the aforesaid applications, and need not be further described here, as the same forms no part of the present invention.

I claim as my invention:

10. 1. A container for use in filter presses, provided with a passage having openings therefrom into its interior, whereby a suitable cleansing medium is so projected as to flush the entire interior of the container, and a suitable opening through which the unfilterable component is washed out.

20. 2. A container for use in filter presses, provided with a plurality of passages having openings from each into its interior, whereby a suitable cleansing medium is so projected as to flush the entire interior of the container, and a suitable opening through which the unfilterable component is washed out.

25. 3. A container for use in filter presses, provided with a plurality of passages having openings from each into its interior, whereby a suitable cleansing medium is so projected as to flush the entire interior of the container, and a plurality of suitable openings through which the unfilterable component is washed out.

35. 4. A container for use in filter presses, provided with a passage having openings therefrom into its interior, whereby a suitable cleansing medium is so projected as to flush the entire interior of the container, a suitable opening through which the unfilterable component is washed out, and a channel through which liquid gas or vapor is introduced into the plates for treating the material in place.

40. 5. A container for use in filter presses, provided with a plurality of passages having openings from each into its interior, whereby a suitable cleansing medium is so projected as to flush the entire interior of the container, a suitable opening through which the unfilterable component is washed out, and a channel through which liquid gas or vapor is introduced into the plates for treating the material in place.

45. 6. A container for use in filter presses, provided with a plurality of passages having openings from each into its interior, whereby a suitable cleansing medium is so projected as to flush the entire interior of the container, and a plurality of suitable openings through which the unfilterable component is washed out, and a channel through which liquid gas or vapor is introduced into the plates for treating the material in place.

50. 7. In a container for use in filter presses, the combination of a feed inlet through which the material to be treated is admitted, a passage having openings therefrom into its interior, whereby a suitable cleansing

medium is so projected as to flush the entire interior of the container, a suitable opening through which the unfilterable component is washed out, and a channel through which liquid gas or vapor is introduced into the plates for treating the material in place.

55. 8. In a container for use in filter presses, the combination of a plurality of feed inlets through which the material to be treated is admitted, a plurality of passages having openings from each into its interior, whereby a suitable cleansing medium is so projected as to flush the entire interior of the container, a suitable opening through which the unfilterable component is washed out, and a channel through which liquid gas or vapor is introduced into the plates for treating the material in place.

60. 9. In a container for use in filter presses, the combination of a feed inlet through which the material to be treated is admitted, a plurality of passages having openings from each into its interior, whereby a suitable cleansing medium is so projected as to flush the entire interior of the container, and a plurality of suitable openings through which the unfilterable component is washed out, and a channel through which liquid gas or vapor is introduced into the plates for treating the material in place.

65. 10. A container for use in filter presses, provided with a passage having openings generally upward, whereby a suitable cleansing medium may be so introduced into its interior, and an independent outlet from the lower part of said container, through which the unfilterable component is washed out.

70. 11. A container for use in filter presses, provided with a passage having a series of openings generally upward, whereby a suitable cleansing material may be so introduced into its interior, and an independent outlet from the lower part of the said container, through which the unfilterable component is washed out.

75. 12. A container for use in filter presses, provided with a passage having openings generally upward, whereby a suitable cleansing medium may be so introduced into its interior, and a series of independent outlets from the lower part of said container, through which the unfilterable component is washed out.

80. 13. A container for use in filter presses, provided with a passage having a series of openings generally upward, whereby a suitable cleansing medium may be so introduced into its interior, and a series of independent outlets from the lower part of said container, through which the unfilterable component is washed out.

85. 14. A container for use in filter presses, provided with a passage having openings therefrom into its interior, whereby a suitable cleansing medium is so projected as to flush the

the entire interior of the container, a suitable opening through which the unfilterable component is washed out, and a plurality of inlets through which liquid gas or vapor is introduced into the plates behind the filtering medium for treating the material in place.

15. A container for use in filter presses, provided with a plurality of passages having openings from each into its interior, whereby a suitable cleansing medium is so projected as to flush the entire interior of the container, a suitable opening through which the unfilterable component is washed out, and a plurality of inlets through which liquid gas or vapor is introduced into the plates behind the filtering medium for treating the material in place.

16. A container for use in filter presses, provided with a plurality of passages having openings from each into its interior, whereby a suitable cleansing medium is so projected as to flush the entire interior of the container, and a plurality of suitable openings through which the unfilterable component is washed out, and a plurality of inlets through which liquid gas or vapor is introduced into the plates behind the filtering medium for treating the material in place.

17. In a container for use in filter presses, the combination of a feed inlet through which the material to be treated is admitted, a passage having openings therefrom into its interior, whereby a suitable cleansing medium is so projected as to flush the entire interior of the container, a suitable opening through which the unfilterable component is washed out, and a plurality of inlets through which

liquid gas or vapor is introduced into the plates behind the filtering medium for treating the material in place.

18. In a container for use in filter presses, the combination of a plurality of feed inlets through which the material to be treated is admitted, a plurality of passages having openings from each into its interior, whereby a suitable cleansing medium is so projected as to flush the entire interior of the container, a suitable opening through which the unfilterable component is washed out, and a plurality of inlets through which liquid gas or vapor is introduced into the plates behind the filtering medium for treating the material in place.

19. In a container for use in filter presses, the combination of a feed inlet through which the material to be treated is admitted, a plurality of passages having openings from each into its interior, whereby a suitable cleansing medium is so projected as to flush the entire interior of the container, and a plurality of suitable openings through which the unfilterable component is washed out, and a plurality of inlets through which liquid gas or vapor is introduced into the plates behind the filtering medium for treating the material in place.

In testimony, that I claim the foregoing as my invention, I have signed my name in presence of two witnesses, this sixth day of April 1906.

CHARLES W. MERRILL.
